UNITED STATES PATENT OFFICE.

AUSTIN C. JOHNSON, OF CHICAGO, ILLINOIS, ASSIGNOR, BY MESNE ASSIGNMENTS, TO PRODUCTION METER COMPANY, OF CHICAGO, ILLINOIS, A CORPORATION OF DELAWARE.

MACHINE-RECORDER.

1,323,062.

Specification of Letters Patent. Patented Nov. 25, 1919.

Application filed September 12, 1912. Serial No. 719,937.

To all whom it may concern:

Be it known that I, AUSTIN C. JOHNSON, a citizen of the United States, residing at Chicago, in the county of Cook and State of Illinois, have invented certain new and useful Improvements in Machine-Recorders, of which the following is a specification.

My invention relates to recording devices and has particular reference to a novel indicating and recording meter for use in connection with the machines in operation in manufacturing establishments.

One of the principal objects of this machine is to establish the only equitable basis on which to pay labor,—the productive-hour basis. It has been found that both day work and piece work retards rather than increases output and that if an absolutely reliable meter could be built which would accurately record the net producing time of each operator, (without the enormous delay and expense of installing so-called efficiency systems), so that he could be paid a greatly increased hour rate for producing time and a correspondingly reduced rate or nothing at all for idle time, (for which he alone was responsible), it would in time eliminate labor troubles, greatly enhance the earning capacity of the average workman and materially reduce the cost of production.

In the preferred form, the operative and inoperative periods of the machine are automatically registered on a chart and the operative periods simultaneously accumulated to the end that performance of the machine in the shop shall be in constant view, and at the end of the day or other period of operation the total of all the productive work of the machine for that period shall be at hand. My invention contemplates a device which may be located at a point removed from the machine the work of which is to be registered, which device shall include a constantly movable visible sheet, means for marking on the sheet the operative and inoperative periods of the distant machine, together with means in the form of an accumulator which registers the total of the operative work performed by the distant machine during any given period.

Mechanism by means of which some of the above-named objects may be attained, I believe, old in the art. However, it has been found difficult to provide mechanism which shall record the periods of operation with

absolute accuracy, and exhibit at a glance the net production time from the full running time of any operator or machine without analyzing the whole chart, which would be practically impossible, owing to the minute delays occurring on certain machinery. For this purpose I have provided an accumulator which differentiates between idle and producing time and totals productive time only as it occurs during the day.

It will be understood that such devices are often applied to machines which operate with great rapidity, such for instance, as punching machines, in which an operation may require but one second; assuming an inoperative period of an equal duration, it will be seen that the recording machine must register 30 operations and 30 periods of rest each minute. If the recording device fails to register with absolute accuracy the duration of each operation, even to a fraction of a second, the total time for the entire day will be decidedly inaccurate and unsatisfactory as a basis on which to compensate the workman. Thus, a machine in order to be satisfactory to the employer and workman must be unquestionably accurate. I have found that to attain this accuracy the recording device must be of an exceedingly simple form, including the smallest possible number of working parts, and must be driven in the most direct manner possible. By securing a substantially direct drive any back-lash is eliminated. Furthermore, I have discovered that the brake by means of which the recording device is stopped and permitted to start must be applied directly to the recording element. There being no interposed gearing, the opportunity for back-lash or play is reduced to a minimum.

It is the custom to provide a device of this sort which shall have operative connections with a large number of, say fifty, machines in a shop. This requires fifty marking devices and fifty accumulators. My invention contemplates the employment of a pair of drums upon which a sheet of paper may be mounted, this drum being operated by suitable clock mechanism; and a series of accumulator units, one for each machine to be registered, each unit being removable, adjustable, and self-contained; that is, the unit which is bodily removable contains the entire mechanism by means of which the visual marking is accomplished and the total

of operative time of the machine registered. An advantage resulting from this construction is in that any one of the units which may become inoperative from any cause may 5 be quickly disengaged and another substituted without stopping the operation of the machine or the other units, or causing a material break in the accumulation of time of the machine connected thereto. A further 10 object in the provision of the unitary recording devices is in that the unit including the marking device may be adjusted with relation to the marking roll.

It will be understood also that at the end 15 of each working period a fresh sheet of paper must be applied to the drums and the marking devices set back to naught. In my construction this is accomplished by novel mechanism and without unnecessary loss of 20 time.

My invention will be more readily understood by reference to the accompanying drawings, in which—

Figure 1 is a front elevation of a machine constructed in accordance with my invention;

Fig. 2 is a side elevation with the outer casing broken away;

Fig. 3 is an enlarged side elevation similar 30 to that shown in Fig. 2.

Fig. 4 is a plan view partly in section showing a number of accumulator units and the actuating means therefor;

Fig. 5 is an enlarged front elevation 35 partly in section;

Fig. 6 is an enlarged detail elevation of my novel unit, showing accumulator wheel and the magnetic control for the marking device;

Fig. 7 is a section on the line 7—7 of 40 Fig. 6;

Fig. 8 is an enlarged detail elevation of a portion of the power-shaft showing the mounting of the unit-operating gears;

Fig. 9 is a side elevation of the accumulator gear, the view being taken from the opposite side to that shown in Fig. 6;

Fig. 10 is a detail of the rod carrying the bent pins by means of which the marking arms are moved, thus releasing the 50 brakes from the accumulator gear wheels during the re-setting of the wheels, and

Fig. 11 is an enlarged elevation of the dial appearing on the units.

Referring more particularly to the drawings, it will be seen that I provide a base 20 supported by suitable legs and carrying an outer casing 21, the front face 22 of which is preferably composed of glass in 55 order that the operation of the machine may be observed. Projecting upwardly from the base 20 are brackets 23 carrying suitable bearings, within which is mounted a shaft 24, supporting a drum 25. Projecting from 60 each bracket 23 is an integral arm 26 carry-

ing a bearing in the end thereof, within which is mounted a shaft 27 supporting an idle roller or drum 28. A standard 29 is projected upwardly from the arm 26, being seated in a bearing 31 therein. This standard is provided at its upper end with a bearing within which a shaft 32 is mounted, this shaft carrying a drum 33. In practice, a sheet of paper is mounted on the drums 25, 28, and 33 and is caused to travel 75 with the rotation of the drums. Motion is transmitted to the shaft 24 by a large gear 34.

Projecting upwardly from the base 20 are small brackets 35, 35, within which are pinned transverse shafts 36. These shafts 80 serve as guides or ways for the support and control of a table 37 having downwardly-projecting bearing-ports 38, 39 thereon. These bearing-ports coöperate with the shafts 36, sliding thereon as the table is 85 moved longitudinally of the shafts. One of the bearings 39 is bifurcated at its lower end and accommodates a cam 40, mounted on shaft 41. This shaft 41 is mounted in bearings 42 at either end of machine, as 90 best shown in Figs. 4 and 5. A handle 43 operatively connected to the shaft 41 permits the rotation of the same in order to accomplish the backward and forward movement of the table within the limits allowed 95 by the throw of the cam.

Upon the table 37 are carried upwardly-projecting brackets 44 at either end of the machine, these brackets being provided with bearings at their upper ends within 100 which is mounted the transverse power-shaft 45. This shaft carries at one end a clock mechanism 46 and on the other end a suitable weight 47, by means of which the shaft is caused to rotate as permitted 105 by the clock movement. The shaft 45 takes the place of the spring barrel in the clock mechanism, there being no spring employed.

A handle 48^a is provided on shaft 45, whereby the weight may be elevated or rewound, and for another purpose, later to be described. The shaft 45 is provided at either end with pinions 48 meshing with the large gears 34 connected to the drum-shaft 24. Thus, the motion of the shaft is 115 transmitted to cause the travel of the chart or sheet mounted on the drums.

As shown in Fig. 8, the pinion 48 is provided with a sleeve 49, through which is passed a pin 50. Thus the pinion 48 is 120 caused to rotate with the shaft 45. At intervals in the length of the shaft 45, collars 51 are mounted, these being suitably secured to the shaft by means of pins 52. Gears 53 are mounted between the collars 51 and 125 are held in proper relation by means of flat springs 54. Thus the gears 53 are frictionally held on the shaft 45.

Extending between the brackets 44 is a bar 55 carrying on one side of its face a 130

plurality of electric contact members 56 to which electric conductors 57 are connected (Fig. 3). Also extending between the brackets 44 is a bar 58 having a plurality 5 of set-screws 59 therein. These set-screws serve as abutments or stops for the units about to be described.

The units which form an important part of my invention are of extremely simple 10 construction and are composed of a frame 60, having a slot 61 in the base, Fig. 6, and provided with bearings within which a short shaft 62 is mounted. This shaft carries on its overhung end a marker arm 15 63, having a suitable marking device 64 at its free end. This shaft 62 has suitably secured thereto an iron plate 65, which plate, at its upper end acts as a brake on the accumulator gear later to be described, and 20 at its lower end coöperates with the cores 66 of suitable magnets 67. Electrical connections are made between the magnets and two terminals 68, which terminals coöperate with the spring contact members 56, as best 25 shown in Figs. 3 and 4. The iron plates 65 are normally held out of contact with the cores 66 by means of a compression spring 69 held in an apertured lug 70 formed as a part of frame 60. Thus, when the 30 magnets are deenergized, plate 65 is moved, and its upper end brought into braking contact with the accummulator gear. It will be understood, that each movement of the plate 65 rocks shaft 62 and so causes a 35 corresponding movement of the marker 63.

The accumulator of my invention comprises a large gear 71 mounted on a short shaft 72 held by the walls of the casing 73. This gear is provided on one face with a 40 spiral groove 74, within which a pin 75 fixed in a pivoted lever 76 may travel. The lever 76 is pivoted at 77 to the casing 73. The number of turns of the spiral is optional. However, in practice, I prefer to provide 45 twelve, each groove representing an hour, it being intended that the gear 71 shall rotate once each hour of operative production of the machine connected thereto. Also mounted on the shaft 72 is a cam 78, this cam 50 being held against the gear 71 by means of compression spring 79. The cam 78 is not keyed or pinned to the shaft 72 and is thus permitted to rotate on the shaft against the friction generated by the pressure of the 55 spring. The arm 80 pivoted to a pin 81 held by the casing 73 is operated by the cam 78 through coöperation with a pin 82 on the lever. During normal operation, the cam 78 travels with the shaft 72 and the gear 60 71 and causes the travel of the arm 80 through its entire arc of movement for each revolution. After the arm reaches the highest point of the cam, as shown in Figs. 6 and 9, the pin will pass over the point and allow 65 the arm to drop. The gear 71 meshes with

one of the gears 53, which are frictionally held on power-shaft 45. Thus, for each revolution of the power-shaft, the accumulator gear and the cam 78 rotate an equal amount. The arm 80 controlled by the cam 78 70 registering minutes, and the arm 76 controlled by the spiral groove registering hours, it will be seen that when the shaft 72 has made a complete revolution, the indicator will show that sixty minutes of time 75 have been accumulated. This accumulation of sixty minutes may have extended over several hours of elapsed time, the amount indicated on the accumulator being only the amount of actual productive time of the 80 machine. The marker 63 is placed whereby its point 64 is in engagement with the chart on the drums, as shown in Fig. 3. At each break in the electric current the iron plate 65 is moved, thus causing a corresponding 85 movement of the marker, which movement is indicated on the chart. When the current is on, which indicates that a machine is in operation, the magnets withdraw plate from contact with the gear 71, thus permitting 90 it to rotate under the drive of the gear 53 on the power-shaft 45. When the current is off, indicating a machine not in operation, the coil spring 69 will force the plate 65 into braking engagement with the ac- 95 cumulator gear 71, preventing its rotation. This causes slippage of the gear 53 on shaft 45.

In Fig. 6 I have shown diagrammatically, a circuit by means of which the operative 100 production of a machine is registered. In that view it will be seen that a conductor extending from one of the terminals 68, passes first to a switch 83, which is controlled by the belt shifter of the machine. 105 The conductor then extends to another switch 84 controlled by the passage of material through the machine. In this instance, I have shown the machine as a planer having a bed 85, planer roll 86 and a piece 110 of lumber 87 passing through the machine. It will be seen that as the material passes through the machine the switch 84 is actuated, thus closing the circuit. A suitable battery or other source of electric energy is 115 interposed in the circuit. The circuit is not closed, and the recording machine actuated, until the switch controlled by the belt shifter is closed, thus beginning the operation of the machine, and work is passing through 120 the shop machine. Thus, if the belt shifter were thrown and the shop machine running idle without work passing therethrough, the indicator would show the machine to be idle; also, if work were placed in the machine 125 and the belt shifter reversed, the recording device would show the machine to be idle.

The units described are secured to the table 37 by suitable set-screws 88, the table being slotted, as at 89 in Fig. 6, to permit a 130

slight longitudinal adjustment of the unit as required in order to bring the marking point 64 into proper relation with the chart. The groove 61 in the bottom of the unit operates with a rib 90 on the table 37, thus centering the unit as required. The inner stop or abutment for the unit is the set-screw 59 as heretofore described.

After the completion of a day's work, or a given period of operation, the totals of the accumulator units are recorded and the accumulators re-set at naught. This is accomplished as follows:

First, the operator by means of the handle 15 43, rotates the shaft 41 carrying cams 40. The table 37 carrying the power-shaft 45 and the different units is retracted, thus disengaging the pinion 48 from the gear 34. A new chart or sheet is then supplied to the 20 drums. While the table is held in its retracted position the handle 48^a is rotated, thus moving the power-shaft and winding up the weights 47. This action tends to rotate the gears 53, which are frictionally 25 held on said shaft 45. However, as the machines in the shop are presumably inoperative at that time, the accumulator gears will be prevented from rotation because of the brakes 65. Thus the accumulators could 30 not be re-set. I have, therefore, provided as shown in Fig. 5, and in detail in Fig. 10, a bar 91 suitably connected to brackets 92 secured to the bracket 26. On the bar 91 I provide a plurality of bent pins 93 lying 35 in the plane of the upper ends of the markers 63. As the table 37 carrying the units is retracted, the markers contacting the pins 93 will be moved and plates 65 disengaged from the accumulators gear 71. Then, when 40 the crank 48^a is rotated, the accumulator gear will likewise be rotated and the indicator levers 76, 80 returned to normal position. It will be understood that only one rotation is necessary to return the marker 80 to its 45 lowermost position and that a relatively larger number of rotations are necessary to return the indicator 76 in view of the fact that such indicator must return through the series of spiral grooves. Therefore, the 50 cam 78 is provided with a frictional engagement with the shaft 72, permitting said shaft 72 and gear 71 to be reversed.

The connection of the shaft 45 to the clock movement must likewise be non-positive in one direction, as will be well understood. I have, therefore, provided a pair of disks 94, 55 95, the former being pinned to the shaft and carrying a pawl and the latter being connected with the clock mechanism and carrying a ratchet. Thus, in one direction the connection with the clock mechanism is positive, whereas in the opposite direction it may be rotated freely.

The indicators 76 and 80 are provided at 60 their free ends with pointers 96, 97. These

pointers travel on a curved dial 98 formed as a portion of the accumulator casing 73 of the units. This is shown in detail in Fig. 11.

After the accumulators have all been set 70 to naught and the weight 47 raised, the handle 43 is again rotated, returning the table to its former position and bringing the markers into engagement with the chart and the pinions 48 in engagement with the gears 75 34. The machine is then ready for another series of operations.

It will be noted by the construction described, that the accumulator mechanism is very directly connected to the power-shaft, 80 there being but one gear connection between the two. The possibility of inaccuracy is, therefore, practically eliminated. Furthermore, by the extreme simplicity of the construction, the liability of the device becoming inoperative is reduced. In case, however, any unit should become inoperative for any reason that unit may be quickly disengaged and another supplied without interrupting the operation of the other units. 85 This is an important advantage, and I consider the provision of the unitary self-contained adjustable units as an important feature of my invention.

The instrumentalities herein described are 90 in many cases typical, and are subject to many modifications. Such modifications as are within the scope of my claims I consider within the spirit of my invention.

I claim:

1. The combination with a continuously moving record sheet, of an electric circuit, a switch, means for automatically and intermittently actuating said switch to close said circuit, and a recording unit interposed in 105 said circuit, said recording unit being arranged to make a continuous record on said sheet during a predetermined position of said switch, and being readily detachable from said circuit as a unitary structure 110 without affecting the mechanism for imparting continuous movement to said record sheet.

2. The combination with a record sheet, of an electric circuit comprising a switch 115 and an electrically actuated recorder arranged to make a continuous record on said sheet during a predetermined position of said switch, said recorder being slidably connected in said circuit so as to be detachable therefrom without said record and its immediate actuating mechanism, being slidably connected in said circuit so as to be detachable therefrom as a unitary structure. 120

3. The combination with a record sheet, 125 of an electric circuit comprising a switch, an electrically actuated recorder arranged to make a continuous record on said sheet during a predetermined position of said switch, an accumulator arranged to currently record 130

- the totals intermittently or continuously recorded by said recorder, a drive mechanism, a friction gear interposed between said drive mechanism and said accumulator, and
- 5 an electrically operated brake adapted to stop the operation of said accumulator during a predetermined position of said switch, said accumulator and said switch being assembled as a unit slidably connected in said
- 10 circuit and with said drive mechanism so as to be detachable therefrom as a unitary structure.
4. The combination with a record sheet, of an electric circuit comprising a switch automatically and intermittently actuated to close said circuit, and a recording and accumulating unit interposed in said circuit and adapted to make a continuous record on said sheet during a predetermined position
- 15 of said switch, the accumulating element of said unit being arranged to show currently the totals of said record, said unit being detachable from said circuit as a unitary structure.
- 20 5. The combination with a continuously moving record sheet, of drive mechanism for moving said sheet, an electric circuit, a switch automatically and intermittently actuated to close said circuit, a recorder interposed in said circuit and arranged to make a continuous record on said sheet during a predetermined position of said switch, an accumulator driven in synchronism with said sheet moving mechanism, and a brake
- 25 arranged to stop the drive of said accumulator during a given position of said recorder and to release said accumulator during a different position of said recorder whereby said accumulator may show currently the totals of the record made by the recorder when in a given position, said recorder being readily removed from said circuit as a unitary body without affecting the
- 30 operation of the record sheet driving mechanism.
- 45 6. The combination with a continuously moving record sheet, of an intermittently operated recorder adapted when in a certain position to make a continuous record on said sheet, an accumulator comprising a pointer arm adapted to show the totals of such records, a pointer arm adapted to indicate a fractional part of said totals, a brake normally set to prevent the operation of said accumulator, but actuated by the movement of the recorder in the recording position to release the accumulator.
- 50 7. In a device of the class described, an accumulator comprising a plate provided with a spiral groove on one side, a pointer arm provided with a pin resting in said groove whereby the rotation of said plate will progressively change the position of said pointer arm to indicate the totals by
- 55 certain mechanical operations, and a second
- pointer arm adapted to be moved from the lowest point of record to the highest point of record for each complete revolution of said plate.
8. In a device of the class described, an accumulator comprising a plate provided with a spiral groove on one side, and a pointer arm provided with a pin resting in said groove whereby the rotation of said plate will progressively change the position of
- 60 said pointer arm to indicate the totals by certain mechanical operations, said plate being provided on its opposite side with a cam having a straight face extending on a line from its highest point to its axis, and a progressively curved face from the bottom of said straight face to said highest point, a pointer arm provided with a pin adapted to ride upon said curved face until said arm has been caused to travel to a point of maximum record whereupon said pin drops over said straight face and said arm is carried back to the point of lowest record.
9. In a device of the class described, a time recorder or accumulator consisting of a disk provided on one face with a cam having a straight face radial to said disk, and a progressively curved face leading from the lowest point of said straight face to the highest point thereof, a pivoted record arm provided with a pin adapted to ride on or against the faces of said cam whereby said record arm is carried from the highest record point during each rotation of said disk and is automatically dropped back to the point of beginning, the opposite faces of said disk being provided with a spiral groove and a pivoted record arm provided with a pin arranged to ride in said spiral groove whereby the rotation of said disk will cause said record arm to progressively travel from the point of lowest record to the point of maximum record.
10. In a machine of the class described, the combination with a continuously moving record sheet, of drive mechanism therefor, an electric circuit, a switch intermittently and automatically actuated to close said circuit, a recorder automatically moved to recording position against said sheet by the closure of said circuit and automatically moved to a different position by the opening of said circuit, an accumulator arranged to automatically and currently record the totals of the records made by said recorder when in a given position, said recorder and accumulator being combined in a single unit detachable as an entirety from said circuit and mechanism.
11. In a machine of the class described, a removable recording and accumulating unit comprising drive mechanism, a friction gear between said drive mechanism and the accumulating element of said unit, means for intermittently and automatically actuating
- 65
- 70
- 75
- 80
- 85
- 90
- 95
- 100
- 105
- 110
- 115
- 120
- 125
- 130

said recorder, and means for permitting said accumulator to operate only during a certain position of the recorder and for preventing such operation during any other position of said recorder, said accumulating and recording unit being so assembled as to be removable from said machine as an entirety.

12. The combination of a record sheet, 10 and means for moving the same, a plurality of separately removable accumulating units, means associated with said units adapted to mark said sheet, electrically controlled means for actuating said accumulating and 15 marking mechanisms, and means actuated by the operation of a shop machine to close an electric circuit to actuate said electrically controlled means.

13. In a recording device, the combination 20 of a movable record sheet, a marker, an accumulator and a single magnetically actuated means for controlling both the marker and the accumulator, said marker, accumulator and controlling means being 25 associated in a single housing and removable as a whole from its connection with the drum, an electric circuit, and means actuated by the operation of a shop machine for closing said circuit to actuate said magnetically 30 actuated means, substantially as described.

14. In a recording device, the combination 35 of a base, a drum mounted on said base and carrying a chart, a plurality of marking and accumulating units mounted on said base and adapted for synchronous movement with said chart, said marking and accumulating units being each independently removable from said base, substantially as 40 described.

15. In a recording device, the combination 45 of a base, a drum and a chart carried by said drum, a plurality of independent removable marking and accumulating devices 50 associated with said base and adapted to cooperate with said chart, means for synchronously actuating said chart and said marking and accumulating devices, a single electrically actuated means for controlling both 55 said marker and said accumulator, an electric circuit, and means actuated by the operation of a shop machine for closing said circuit to actuate said controlling means, substantially as described.

16. In a recording device, the combination 55 of a base, a chart movably mounted on said base, a table mounted for limited movement relative to said base, a plurality of marking and accumulating devices mounted on 60 said table, means for actuating said chart and said marking and accumulating devices, said last named device being adapted

to be disconnected from said chart upon movement of the table in one direction, substantially as described.

65

17. In a recording device, the combination of a base, a chart superposed on said base and adapted for travel relative thereto, a table mounted for limited movement toward and from said chart, a power shaft carried 70 by said table, clock mechanism for causing the rotation of said power shaft, a plurality of marking and accumulating devices mounted on said table and in operative engagement with said power shaft, and means 75 for moving said table toward and from said chart, substantially as described.

70

18. A combined marking and accumulating unit, comprising in combination, a frame, a marker, an accumulator gear, a pointer arm controlled by said gear to indicate the total of predetermined periods, a second pointer arm adapted to indicate a fractional portion of one of said periods, and a single electrically controlled means for 85 actuating said marker and permitting the operation of said pointer arms, substantially as described.

80

19. In a combined marking and accumulating unit, the combination of a frame, an oscillatory marker, a magnet for controlling 90 the oscillation of said marker, an accumulator gear rigidly mounted on a shaft, an accumulator cam non-positively mounted on the same shaft, and indicating devices operated by said gear and said cam, substantially as described.

90

20. In a combined marking and accumulating unit, the combination of a frame, an oscillatory marker mounted in said frame, a magnet controlling the oscillations of said marker, an accumulator wheel, one face of which contains a spiral groove, an accumulator cam, means for actuating said wheel and cam and indicating devices co-operating 105 with the groove in said wheel and with the surface of said cam, substantially as described.

95

21. The combination with a continuously moving record sheet and means for operating the same, of a plurality of accumulating units adapted to be operated by said operating means, each unit comprising a marking arm and a brake for the accumulating unit arranged to move in unison with said marking arm, means whereby all of said marking arms may be simultaneously operated to release all of said brakes, in combination with means for reversing the movement of said accumulators.
